BRACELET

Hyman Dinstman, New York, N. Y., assignor to
 I. D. Watch Case Co. Inc., Jamaica, N. Y., a
 corporation of New York

Application April 13, 1948, Serial No. 20,692

7 Claims. (Cl. 224—4)

1

This invention is concerned with improvements in a clasp bracelet of the type comprising a central body portion having a pair of arcuate arms hingedly mounted at opposite ends thereof for engagement around the wearer's wrist.

The invention is concerned specifically with improvements in bracelets of this type wherein the central body portion is in the form of a watch case of relatively light construction.

One object of the invention is to provide a hinged connection of the arcuate arms to the watch case body to permit abnormal hinged or swinging movement of said arms on the body without subjecting it to excessive strain.

A further object of the invention is to provide a hinged support for connecting the arcuate arms of a bracelet to the central body or supporting portion of the bracelet which permits, against spring biased resistance, relative movement of each arm, first against one spring and then, upon continued movement, against both springs.

Other and more detailed objects of the invention will be apparent from the following description of the embodiment thereof illustrated in the attached drawing.

In the accompanying drawing—

Figure 1 is a side elevational view of a structure in accordance with this invention showing the bracelet in closed position;

Figure 2 is a similar view somewhat enlarged along a central plane showing in cross section in greater detail the structure of the invention;

Figure 3 is a view similar to Figure 2 of the right hand portion of the bracelet showing one of the arms fully opened;

Figure 4 is an elevational view similar to that of Figure 2 with portions of the arms omitted showing them fully swung open;

Figure 5 is a cross sectional detailed view taken on the line 5—5 of Figure 2; and

Figure 6 is a detailed view of one of the hinged joints on a cross sectional plane similar to the smaller view of Figure 2.

In the bracelet art there is a type of bracelet made consisting of a central body portion in the form of a watch case which, as is usual for watch cases, is made in the form of a relatively thin metal housing having a removable back and a transparent front or crystal. Pivotally mounted on the end walls of this housing are a pair of spring biased clasp arms which complete in essence the bracelet structure and by means of which it is attached on and detached from the wearer's wrist. The clasp arms are pivotally mounted on the watch housing and have a rela-

2

tively limited swinging movement on their pivotal supports. As a result, should the wearer's wrist be larger than that for which the bracelet is designed the wearer in attaching it to the wrist naturally tends to open the arms an amount greater than that allowed by the limited pivotal swinging movement of the arms on the housing. As a result, the relatively thin walled metal housing is subjected to a bending force in a direction which causes the back of the housing to fall out since the back is usually held in place by snap action, i. e. frictionally.

The purpose of this invention is to provide a similar construction in which the clasp arms are double spring biased and are pivotally mounted on the watch case housing, each on a pivot point arranged so that normal swinging movement of the arms against resistance of one spring will allow the attachment of the bracelet to the wrist under all normal circumstances. However, in the case of a wearer who has a larger than normal wrist for which the watch is designed, it is possible to open the clasp arms a still greater distance by continued outward swinging movement at which time rotation is against the reaction of both springs. The arms are each urged back to normal closed position when released first by both springs and then by one spring only. It will be seen that the additional swinging movement provided will prevent the application of a bending stress to the watch case housing at least until the movement has reached the limit for which the structure is designed. However, at that time the clasp arms are swung so widely apart that the bracelet may be attached to any size wrist likely to be encountered. Indeed, with this construction the bracelet may be attached to a wrist on which it would look unsightly. In other words, the structure will permit the application of the bracelet to wrists so large that it is clearly not intended for use under such conditions. The result is that the watch case housing is not likely to be strained, and the back does not tend to fall out, a condition which this invention seeks to obviate.

The attainment of these objects will be apparent from the following description of the embodiment of the invention illustrated in the attached drawing as one form of the invention. The central or main body portion of the bracelet comprises a watch case housing consisting of the housing 1, the snap-on cover 2 and the crystal 3. The small hole at 4 in Figure 1 provides the opening through which the stem of the watch may project for attachment of the housing knob.

Rigidly attached to the opposite ends of the housing portion 1 are a pair of U-shaped supports 5 and 6 which may be attached to the housing by any of the usual methods employed in this art. It is to be noted that if desired and if practical, these supports 5 and 6 may be made integral with the watch housing 1. Pivoted in supports 5 and 6 on the pivot pins 9 and 10 respectively are the clasp arms 7 and 8. These pivot pins extend between the side walls of the U-shaped supports 5 and 6 and the ends are riveted over or otherwise attached therein. As clearly shown in Figure 2, coil springs 11 and 12 are mounted upon the pivot pins 9 and 10, respectively, with one end of each respectively anchored in a small recess in an adjacent end of each clasp arm 7 and 8. The other end of each of these coil springs rests upon a ledge or seat forming member 23 attached in any suitable manner to the adjacent flat leaf spring of which the leaf spring 22 in Figure 6 is an example and to which reference will be later made.

Nested in the supports 5 and 6 are U-shaped fixtures 13 and 14 which have a shape complementary to the supports 5 and 6 and are secured therein in any suitable manner. The side walls of the members 13 and 14 extend above the side edges of the supports 5 and 6 as clearly shown in Figure 4. As is obvious the pivot pins 9 and 10 also pass through the side walls of members 13 and 14. These side walls extend beyond the bottom wall of each U-shaped fixture to form a pair of projecting side arms as clearly shown in Figures 2, 5 and 6, for example, in which the pivot pins 15 and 16 respectively are secured. Each pivot pin has mounted thereon a sleeve as represented for example by the sleeve 17 on the pivot pin 16, see Figure 6. Attached to these sleeves are a pair of covers or caps 18 and 19 which in the case of the cover 19, see Figure 6, is provided with the extension 19' which projects around the sleeve 17 and to which it is attached in any suitable manner, as by soldering so that the sleeve 17 rotates with the cover 19 on the pivot point 16. The construction at the other side of the bracelet is exactly the same as indicated in Figure 2. The covers 18 and 19 may be of decorative construction and may be provided with jewels or other decorative ornaments 20 and 21.

As clearly shown in Figure 6, the extension 19' of the cover 19 is arranged to engage the free end of the flat spring 22 which has a U-shaped formation at that end, integral with a wider section 22' at the other end. As clearly shown in Figure 5, the wider section 22' is of such length as to fit snugly between the side walls of the member 14 of the bracelet and abuts along its wide free edge against the adjacent edge 14', see Figure 5, of the bottom wall of the member 14. The free end of the U-shaped portion of the spring 22 is arranged to be engaged by the end edge of the extension 19' of the cover 19, as clearly shown in Figure 6. With regard to the details of the other spring 22, and cap 18, it is noted that the construction is the same for the left hand side of the bracelet.

Upon consideration it will be seen that if the springs 22 are of heavier or stiffer construction than the springs 11 and 12 that the arms 7 and 8, upon being pulled outwardly, will first pivot on their pivotal supports 9 and 10 respectively, against the reactions of springs 11 and 12. However, when the arms 7 and 8 swing out far enough to engage the ends of the covers 18 and 19, it

will be seen that they will pivot on their pivot pins 15 and 16 against the resistance of the associated springs 22. Since the covers 18 and 19 can pivot in this manner, it will be seen that they will offer no resistance to the swinging movement of the arms 7 and 8 so that those arms can be swung out into substantially a straight line as indicated in Figure 4, without putting any stress on the watch case 1—2. Of course, when the parts reach the limit of their movement, that is, when the covers 18 and 19 are jammed by the arms 7 and 8, so that no further pivotal movement of the arms and covers can take place, strain is then applied to the watch case housing, but at this time the bracelet arms have opened beyond any possible useful point so that this condition is not likely to be attained in any normal or even possibly abnormal treatment of the structure. When the arms are released the springs 11, 12 and 22 all act to return the arms and covers to their normal positions as shown in Figure 1. From the above description, it will be apparent to those skilled in the art that the structure herein disclosed is admirably adapted to avoid the difficulties of similar prior art structures in a practical manner.

Those skilled in the art will likewise appreciate that the details of construction are capable of some variation without departure from the subject matter herein disclosed. For example, as will be readily apparent various other forms of springs may be substituted for those specifically illustrated. Also, it will be understood that although the advantages of this invention are most effective for use with a thin walled housing having a frictionally attached cover they are also of utility with other forms of central body portions of a type, for example, which may not comprise a watch case housing and may not have a frictionally attached part. I do not therefore desire to be strictly limited to the disclosure as herein given for illustrative purposes but rather by the scope of the claims granted me.

What is claimed is:

1. A bracelet as disclosed comprising a central body portion, a pair of arcuate clasp arms, means for pivotally supporting said clasp arms on opposite ends of said body portion, means for resiliently resisting pivotal movement of said arms and spring biased means independently pivoted on the same ends of said body portion, said arms when pivoted an excessive amount on their pivot pins moving into engagement with said spring biased means to displace them in opposition to their spring bias.

2. In the combination of claim 1 said spring biased means comprising decorative cover members each pivotally mounted at one end and overlying the adjacent ends of said clasp arms at the other.

3. In the combination of claim 1, said last means each comprising a cover member and a flat spring arranged to be tensed by pivotal movement of said cover members.

4. In the combination of claim 1, said last means comprising cover members and flat springs each arranged to be engaged at one end by said cover members and engaging an abutment on said body portion at the other end, and said resilient means comprising coil springs bearing at one end on said flat springs for holding them in position against said abutments.

5. A watch bracelet comprising a central body portion forming a watch case, a pair of clasp arms pivotally supported on an opposite pair of

sides of said watch case, cover members also pivotally mounted at the same sides of said watch case and arranged to overlie the adjacent ends of said clasp arms and spring means for resiliently resisting pivotal movement of said arms and cover members, said cover members being arranged to be engaged by said clasp arms upon a limited movement thereof to cause pivotal movement of said cover members when said clasp arms are moved still further in the same direction.

6. In the combination of claim 5, separate pre-loaded springs for resisting pivotal movement of each of said clasp arms and cover members and holding said arms and cover members in normal closed position, the spring for each of said arms having one end bearing on the spring for the associated cover member.

7. In the combination of claim 5, separate nor-

5

mally flexed springs for holding said arms and cover members in normally closed position and for independently resisting pivotal movement of each of said clasp arms and cover members.
